PLATE TYPE HEAT EXCHANGER

Charles B. Dalzell, Little Falls, N. Y., assignor to
 Cherry-Burrell Corporation, Wilmington, Del.,
 a corporation

Application February 24, 1947, Serial No. 730,422

6 Claims. (Cl. 257—245)

1

This invention relates to apparatus such, for example, as plate type of heat exchangers, filter presses and the like in which a plurality of plate-like elements or plate-like elements and spacers or frame-like elements are operatively supported in a press or frame in close side-by-side juxtaposition. More specifically, this invention relates to the new and novel improvements in the arrangement and construction of the supporting framework and the plate-like elements for the support of the plate-like elements during the operation of the device, and for the support of the plate-like elements during cleaning and inspection of the device, and to a support arrangement wherein the plate-like elements may be readily moved for further inspection, exchange or replacement.

The present invention is particularly well adapted for use in connection with plate type of heat exchangers of the class generally used in the processing dairy products such as milk, etc., and similar foods. In the following description of the invention the preferred embodiment of the invention will be described as a sanitarily designed plate type of heat exchanger of the class commonly used in dairy products processing plants in which the present invention may be readily adapted.

It should, however, be understood that it is not intended or desired to limit the invention to the illustrated and described preferred embodiment thereof.

In the operation of the plate type heat exchangers it has been found that the use of thin metal plates adds appreciably to the heat exchange efficiency which may be attained by the use of such device. The use of relatively fragile heat exchange elements obviously necessitates frequent inspection and examination of the heat exchange element for defects which may develop as the result of usage. Frequent inspection and cleaning is also necessary when such plate type of apparatus is used in connection with the processing of foods. The operation of a plate type of heat exchange apparatus at high heat exchange efficiencies usually entails the employment of rapid flow conditions in the heat exchange media and the associate high pressures in such media. Those operating conditions necessitate frequent removal of the plate-like elements from the press or framework to determine, if possible, whether or not any defects have developed and to permit the correction of observed defects.

It is, therefore, the primary object of this in-

2

vention to provide a new and novel arrangement of a support or press and plate-like element for a plate type of heat exchanger, filter press or the like type of apparatus; in which the individual plate-like elements may readily be moved from operating position, in which they are supported in close side-by-side juxtaposition, to positions in which they are freely accessible for inspection and cleaning, and in which latter position they may be supported independently of other plate-like elements upon a secondary support or they may be supported independently of other plate-like elements upon a primary support and maintained in generally upright position thereon by engagement with a secondary support or stabilizer; in which the individual plate-like elements may be removed from the press or support with relative ease and new or additional plate-like elements added or old plate-like elements replaced; in which the individual plate-like elements when in operative position are supported upon a main support; and in which the plate-like elements are slidably supported on and locked to the supporting framework.

Other objects and advantages of the present invention will be pointed out and more fully described in the following description when read in connection with the accompanying drawings, in which:

Figure 1 is a front elevational view of an improved plate-like element for a plate type heat exchanger embodying the present invention.

Figure 2 is a sectional view taken along line 2—2 of Figure 1 of the drawings.

Figures 3 and 4 are explanatory views illustrating the procedure to be followed in moving plate-like elements from a press or supporting framework from operative positions to positions in which the elements may easily be inspected and cleaned.

Figure 5 is a side elevational view of a plate type heat exchanger, embodying the present invention, in which the plate-like elements and compression elements, as well as spacing and fluid connecting frames or headers, are assembled in operative positions into a support or press.

Figure 6 is a plan view of the plate heat exchanger as shown in Figure 5 in the drawings, in which the auxiliary support or locking rod has been partially removed from operative position in the press and some of the plate-like elements removed from the press.

Referring to the drawings, in which like elements are identified by like numerals, 10 and 11 represent the vertical risers or base elements of

the plate heat exchanger frame or press. The frame or press also includes the transverse and horizontally disposed main or lower support rod 12 and the upper or stabilizing rod 13, all securely fixed together to form a rigid supporting framework or press. The auxiliary support or pivot rod 14 is disengageably secured to the riser 10 by screw threads (not shown) or any other satisfactory conventional arrangement to secure a readily disengageable fastening.

A suitable number of plate-like elements or plates, generally identified by the numeral 15, when in operative position are supported upon the lower support rod 12 in the manner illustrated in Figure 5 of the drawings. The plate-like elements, or plates 15, when in operative position are compressed between the adjacent faces of the vertical riser 10, the compression element 16, and the spacing or header elements 17. The compression element 16 and spacing elements 17 are slidably supported upon and stabilized by the rods 12 and 13 and are provided with suitable openings through which the auxiliary support rod 14 extends.

Each of the rods 12 and 13 is provided at its free end with a hand wheel 18 threaded thereto. Suitable sleeve members 19 are telescoped over the rods 12 and 13 intermediate the hand wheels 18 and the compression element 16, and extend through suitable bushings 26 in the front vertical riser or base element 11. The described arrangement of hand wheels 18 and compression sleeves 19 are used to apply compressive force against compression element 16, and in turn against the plates 15 and spacers or header elements 17, and thus enables the maintenance of the individual plate-like elements 15, spacing elements 17 and compression element 16 in the desired operative relation with respect to one another. The heat exchange media to be used in the plate heat exchanger embodying the present invention may be introduced into the spaces formed between adjacent plates 15 in conventional manners common in the art as, for example, by means of suitable connections and flow passages embodied in the rear riser 10; the spacing or header elements 17, and the compression element 16.

Each of the plates 15 is provided with an inwardly extending lower peripheral slot 20 and an inwardly extending upper peripheral slot 21 positioned along the vertical center line of the plate. These notches are of a dimension slightly greater in width than the dimension of the rods 12 and 13, and are provided with rounded inner ends of a diameter slightly in excess of the diameter of the rods 12 and 13. Each of the plates is also provided with two oppositely positioned apertures 22 and 23. The lower aperture 22 and the upper aperture 23, as clearly shown in Figure 1 of the drawings, are so positioned that a line joining the central portion of the apertures 22 and 23 will bisect a line joining the mid-portions of the slots 20 and 21. The apertures 22 and 23 are spaced laterally of the slots 20 and 21, respectively. In the assembly of the plates 15 into the compression framework of the plate type heat exchanger, each of the plates is supported upon the lower support rod 12 by the engagement of the plate 15 against the rod 12 in such a manner that the rod 12 is received into the slot 23. Likewise, the stabilizing rod 13 is received in the upper slot 21 and the locking rod 14 is received into the upper aperture 23. In this manner each of the plates 15 is securely locked onto the supporting rods 12, 13 and 14 in such a

manner that each of the plates is slidably supported on the rods 12, 13 and 14 but when thus arranged is incapable of lateral motion with respect to the rods 12, 13 and 14. By this same arrangement, it is possible to separate the individual plates one from another when the assembled plates are not compressed, thereby to expose the sides of the plates to make them freely accessible for cleaning or inspection. Any individual plate, when thus separated from the remaining plates of the assemblage, will be maintained in substantially vertical position while resting upon the lower support rod 12 and stabilized against any appreciable transverse tilting by the stabilizing rod 14 which passes through the opening 23 in the upper portion of the plate. By this arrangement it is possible in the compression of the plates 15 in the press of the plate heat exchanger when the hand wheels 18 are tightened to secure the desired accurate alignment between the gaskets 24 of each plate and the adjacent face of the embossed gasket rib 25 in the next juxtaposed plate of the group of plates 15 within the heat exchanger.

When it is desired to clean or inspect any individual plate of the group of plates used in the plate heat exchanger it is necessary only, as clearly illustrated in Figures 3 and 4 of the drawings, to release the compression upon the plates by the appropriate rotation of the hand wheels 18 and the separation of the plates by sliding some of the plates axially along the rods 12 and 13. Having separated a group of plates a sufficient distance adjacent the plate which is to be swung out for inspection or cleaning, it is then necessary only to swing the lower portion of the plate 15 transversely of the remaining assembled plates until the slot 20 is completely disengaged from the lower support rod 12. Having disengaged the slot 20 from the lower support rod 12, plate 15 is then free to be swung laterally of the remaining assembled plates, in the fashion clearly shown in Figure 4 of the drawings, by hingedly swinging the plate 15 upon the auxiliary support rod 14.

Obviously, the dimensions of the rods 13 and 14 and the dimensions of the slot 21 and the aperture 23 must be such as to permit the ready swinging or hinging of the plate 15. Such an arrangement is usually secured by the allowance of sufficient tolerance in the relative dimensions of the rods 13 and 14, the slots 21 and the aperture 23. To replace the plate 15 into the press after it has been swung out first transversely and then laterally to obtain the position illustrated in Figure 4 of the drawings, it is necessary only to reverse the procedure just described for removing the plate 15 from its operative position in the press. To wash the plate-like elements it is necessary only to separate the plates after compression has been relieved, thereby exposing the sides of the separated plates. Lateral tilting of the plates is prevented by the engagement of the walls of the slots 20 and 21 with the adjacent surface of the rods 12 and 13. Excessive transverse tilting of the separated plates is prevented by the engagement of the edge of the plate defining the opening 23 with the adjacent surface of the stabilizing rod 14.

To completely remove a plate 15 from the supporting press or framework it is necessary to disengage the rod 14 from the left vertical riser 10 and to at least partially withdraw the auxiliary support and stabilizing or locking rod 14 from the assembled plates 15, spacers or head-

ers 17, and compression element 16. Having thus removed the rod 14, the pressure upon the plates 15 may be released in the manner heretofore described by the appropriate rotation of the hand wheels 18. The plates 15 may then be separated at the point at which a plate is to be removed from the press. Such separation, as heretofore described, is secured by the axial sliding of the decompressed or released plates 15 along the support rods 12 and 13. Having thus opened the press to the extent generally indicated in the illustrative Figure 3 of the drawings, it is then necessary, first, to swing either the lower or upper end of the plate 15 to be removed transversely of the remaining plates until the slot 20 or 21 has been disengaged from the associated rod 12 or 13. When either the slot 20 or 21 has been disengaged from the corresponding rod 12 or 13 in a manner generally indicated in Figure 3 of the drawings, the disengaged end of the plate may then be swung laterally of the remaining plates a sufficient distance until all of the disengaged end of the plate is entirely clear of the associated support or stabilizing rod, in a manner generally indicated in Figure 4 of the drawings. In this latter position the remaining slot of the plate 15 may then be disengaged from the corresponding support or stabilizing rod and the plate 15 entirely removed from the press. In the event sufficient space is available, the plate may be disengaged from both rods 12 and 13 by extending the transverse tilting of the plate, in which event lateral tilting is, of course, not necessary. To insert a new plate in the press or supporting framework, or to replace an old plate which has been entirely removed from the press in the manner just described, it is necessary only to reverse the procedure just described for completely removing a plate.

It will be observed from the foregoing description that the present invention provides a new and novel arrangement for the support of a plate-like element in a plate heat exchanger or like device, in which the plate-like elements are supported in such a manner that individual plate-like elements may be partially removed from the press, and in that position hingedly supported upon an auxiliary support for cleaning and inspection. The partially removed plate-like element may be readily replaced in the press without disassembling any portion of the remaining plates, headers, spacers or compression elements. It will be equally obvious that according to the present invention a plate or like element may be entirely removed from the press in the manner described after a relatively simple adjustment of the locking or auxiliary support and stabilizing or hinge rod 14.

The described structure is particularly well adapted to permit the separation of the decompression plates and the support of individual plates out of contact with adjacent plates, to permit cleaning thereof without any additional stabilization of the plates and without any undue tilting of the individual plates during cleaning operations.

It will be appreciated that in devices embodying the present invention, the supporting rods readily may be arranged in substantially the same horizontal plane instead of being arranged in substantially the same vertical plane, as illustrated in the drawings of the preferred embodiment of the invention. Similarly, it will immediately be obvious to those skilled in the art that means other than rods may readily be substituted

for the supporting rods referred to in the description of the preferred embodiment of the invention. Accordingly, it is desired that this invention should not be limited to the specifically described vertical arrangement of the plate-like elements and supporting rods or members.

Having thus described the illustrated and preferred embodiment of this invention in a plate or the like type of apparatus, the invention is not to be restricted to the specifically illustrated embodiment thereof, as set forth in the drawings and as heretofore described, except insofar as necessary by the prior art disclosures and the appended claims.

The invention is hereby claimed as follows:

1. A device of the class described comprising, in combination, a press including a lower support rod and an upper stabilizing rod and an auxiliary support rod, a plurality of plate-like elements disengageably hinged to said auxiliary support rod at corresponding ends of said plate-like elements and disengageably supported upon said lower support rod and adapted to swing laterally relative to one another from a position in which the plates are supported in close side by side arrangement upon said lower support rod into positions in which the plates are disengaged from said lower support rod and remain disengageably hinged to said auxiliary support rod.

2. A device of the class described comprising, in combination, a press for a plurality of plates including a fixed base element and a fixed horizontally disposed support element, horizontally disposed auxiliary support means disengageably secured to said fixed base element and spaced from said support element, plate-like elements engaging said support element for disengageable support thereupon, an aperture in each of said plate-like elements through which said auxiliary support means passes, whereby upon the disengagement of said auxiliary support means from said fixed base element said auxiliary support means may be withdrawn through the aperture in said plate-like elements and said plate-like elements disengaged from said support element.

3. A device of the class described comprising, in combination, a press for a plurality of plates, including a fixed base element and a fixed horizontally disposed support element, horizontally disposed stabilizing means disengageably secured to said fixed base element and spaced from said support element, plate-like elements engaging said support element for disengageable support thereon, an aperture in each of said plate-like elements through which said stabilizing means extends, whereby said plates may be supported in substantially vertical position upon said support means and stabilized in such position by said stabilizing means.

4. A device of the class described comprising, in combination, a press for a plurality of plates including a fixed base element, fixed horizontally disposed upper and lower parallel support and stabilizing elements, horizontally disposed auxiliary stabilizing means disengageably secured to said fixed base element and spaced from the upper support and stabilizing element, plate-like elements engaging said upper and lower support and stabilizing elements for support thereupon and stabilization against lateral motion thereby, an aperture in each of said plate-like elements through which said auxiliary stabilizing means extends, whereby individual plate-like elements may be supported upon the lower support and stabilizing element in substantially vertical ar-

arrangement stabilized against appreciable lateral or transverse motion with respect to said upper and lower support means and said auxiliary stabilizing means.

5. A device of the class described comprising, in combination, a press including a lower support rod and an upper stabilizing rod and an auxiliary stabilizing and support rod, a plurality of plate-like elements disengageably hinged to said auxiliary stabilizing and support rod at corresponding ends of said plate-like elements and supported upon said lower support rod and stabilized by said upper stabilizing rod in substantially vertical arrangement in such a manner that the amount of transverse tilting of the plate is limited by the engagement of the plate with the auxiliary stabilizing rod.

6. A device of the class described comprising the combination of a frame having an upper supporting member and a lower supporting member, a plurality of closely spaced plate-like elements each provided with an upper peripheral notch and a lower peripheral notch, said upper and lower notches being engaged with said corresponding upper and lower supporting members with clearance, said plate-like elements being supported on the lower supporting member and stabilized against lateral displacement by said upper supporting member, each of said plate-like elements being provided with an aperture aligned with corresponding apertures in the other plate-like elements, and a longitudinally slidable sup-

porting rod arranged laterally of one of said supporting members and spaced therefrom and removably passed through the aligned apertures in said plate-like elements, said peripheral notches being engaged with the respective supporting members with sufficient clearance so that after the adjacent plate-like elements have been shifted away a sufficient distance from an individual element, the latter can be swung out of its vertical plane until one of the notches clears the corresponding supporting member while said supporting rod is engaged through the aperture of the element.
